Primary Examiner—B. J. Bullock*Assistant Examiner*—Stacia Sinuik*Attorney, Agent, or Firm*—Mark P. Calcaterra[57] **CLAIM**

The ornamental design for a vehicle wheel front face segment, as shown and described.

DESCRIPTION

FIG. 1 is a front perspective view showing my design of a vehicle wheel front face segment;

FIG. 2 is a front elevational view thereof;

FIG. 3 is an enlarged cross-sectional view along the line 3—3 of the FIG. 2; and,

FIG. 4 is an enlarged cross-sectional view along the line 4—4 of FIG. 2.

It will be understood that the cross-hatching shown in broken lines in FIGS. 3 and 4 is for illustrative purposes only and forms no part of the subject design.
